SUCTION CLEANER

Charles G. Troxler, North Canton, Ohio, assignor to The Hoover Company, North Canton, Ohio, a corporation of Ohio

Application March 18, 1938, Serial No. 196,661

8 Claims. (Cl. 35—13)

The present invention relates to suction cleaners in general and particularly to new and novel improvements in dirt-traps for demonstrating the cleaning effectiveness of suction cleaners.

5 In merchandising suction cleaners it is necessary to demonstrate to the prospective purchaser the cleaning effectiveness of the cleaner. The method now practiced is to operate the cleaner over a dirty floor covering, and observe the cleaner pick up the dirt therefrom. In order to convince the purchaser of the amount of dirt removed from the rug it is necessary to remove the cleaner bag and empty the dirt from the bag. Removing and emptying the bag is a disagreeable 10 and dusty operation.

The purpose of this invention is to eliminate these and other disadvantages by providing a demonstration dirt trap which is an accessory for the cleaner and functions without the cleaner bag. 20 In using my invention the usual cleaner bag is removed from the cleaner exhaust and the accessory is attached thereto. The accessory is so constructed as to provide a filter member and an observation glass which are disposed in spaced 25 parallel relation at the rear end of the cleaner, whereby the prospective purchaser can operate the cleaner and observe the dirt laden air swirling within the dirt trap and notice the dirt accumulating in a mass in the dirt trap. Accordingly, 30 the prospective purchaser visually observes the accumulation of dirt in the accessory, without the necessity of removing the dirt from a cleaner bag to determine the cleaning effectiveness and the amount of dirt removed from the floor covering.

35 It is therefore an object of the invention to provide a new and improved accessory to be used with suction cleaners. Another object is to provide a new and improved demonstration dirt trap adapted to be used on suction cleaners, exclusive 40 of the usual cleaner dirt bag. A further object is the provision of a dirt trap adapted for use as an accessory to suction cleaners, and embodying an easily removable air filter. Another object of the invention is the provision of an accessory dirt trap for suction cleaners and which embodies a window and an air filter disposed in spaced parallel relation whereby the observer can 45 watch the foreign matter accumulate as the suction cleaner is moved over the floor covering being cleaned. Other objects and advantages of the invention will be apparent from the specification and drawing wherein:

50 Figure 1 is a rear perspective view of a suction cleaner showing the cleaner filter bag re-

5 moved and the demonstration dirt trap attached to the exhaust of the cleaner;

Figure 2 is a sectional view through the center of the dirt trap, and

Figure 3 is a top plan view partly in section of 5 the dirt trap.

The embodiment of the invention herein disclosed comprises a suction cleaner 10, provided with casing 15 having a nozzle 11 communicating with an unshown fan chamber connected to an 10 exhaust passageway 16 discharging into the usual dust bag, not shown, which is removably supported on a flange 14 at the rear of the cleaner casing. A motor housing 12 is removably secured to the casing 15 by means of a spring 13 rigidly 15 attached to the flange 14, and the housing 12 encloses an unshown motor for driving an unshown fan to create suction to draw dirt-laden air from the surface being cleaned through the nozzle 11 and discharge the same through the ex- 20 haust passageway 16. Suitable wheels 17, only one of which is shown, support the cleaner casing, and the cleaner is propelled over the floor covering by means of a handle 19 which is held in different positions with respect to the cleaner by 25 means of a foot operated mechanism the foot pedal 18 of which is shown.

The demonstration dirt trap comprises a casting 20 provided with a vertical side wall 21 terminating at its lower edge into an inwardly extending bottom flange 22, and projecting from the side wall is a rectangular portion 25 merging into an annular flange 26 provided with oppositely disposed hook-like projections 21, 27 which are adapted to be disposed about a pair of clamping screws 28, 29 to detachably secure the dirt trap to the flange 14 at the discharge end of the cleaner, the clamping screws 28, 29 normally securing the lower end of the usual cleaner filter bag to the exhaust outlet. The flange 26 is provided with an annular recess 29 in which is disposed a sealing gasket 30 to provide an air-tight seal between the exhaust flange 14 and the dirt trap flange 26.

45 A closure plate 33 is pivotally secured, by means of a hinge and pin construction 34, to the bottom of the casting 20 and is normally locked in closed position by means of a latch spring 35 mounted on the cover 33 and which is adapted to engage a pin 36 projecting from the side wall of 50 the dirt trap casing. The cover 33 is provided with a circular opening 37 of less diameter than the opening 38 in the casing bottom wall 22, and the defining edge of the opening 37 is rabbed, as shown at 39, for the rigid reception of a metal 55

disc 40 provided with a plurality of holes 41, the disc forming part of the cover 33. Removably disposed between the bottom wall 22 of the casing 20 and the cover 33 is a filtering member 42 such as lintine, or similar filtering material, which is supported by the perforated member 40 and is clamped in place when the cover 33 is locked to the casing 20. An annular sealing gasket 43 is disposed in a recess 44 of the cover 33 to provide an air tight seal between the casing bottom wall 22, the filter 42 and the cover 33.

The dirt trap casing is provided at its top with an annular shoulder 45 for the reception of an annular gasket 46 and an observation glass 47, and which are held in position by means of a spring retaining member 48 removably disposed in an annular recess 49. The observation glass 47 is parallel to and is spaced from the filtering member 42 and they cooperate with the casing 20 to define a dirt collecting chamber 50. The chamber 50 communicates through a passageway 51 in the casing 20 with the discharge passageway 16 in the cleaner casing 10. The cleaner discharge passageway 16 is disposed at an angle, not shown, with respect to the inlet 51 to the dirt trap and accordingly the air exhausted from the cleaner will be discharged at an angle into the dirt collecting chamber 50 to cause the air to swirl therein prior to escaping through the filtering member 42.

In order to demonstrate the cleaning effectiveness of the cleaner the usual suction cleaner filter bag is removed and the accessory dirt trap is attached to the exhaust of the cleaner by manipulating the clamping screws 28, thereby placing the discharge passageway 16 and the dirt collecting chamber 50 in air tight communication. The motor is energized and rotates the fan which creates suction, and as the cleaner is propelled along the floor covering the dirt laden air is drawn through the nozzle 11 and is discharged through the exhaust passageway 16 into the dirt collecting chamber 50.

Foreign matter will collect in the dirt chamber 50 and the air will pass through the filter member 42 and through the holes 41 in the perforated disc 40 to the atmosphere. All foreign matter is removed from the air as it passes through the filter member 42 so that only clean air is discharged into the atmosphere. As the foreign matter is discharged into the demonstrating dirt chamber 50 it collects into a mass as shown at 55 in Figure 1. This ball of dirt is rotated around the dirt chamber 50 due to the tangential discharge of the dirt laden air into the dirt chamber. And as the ball of foreign matter rotates it collects the dirt in the dirt laden air and gradually becomes larger. The window 47 being parallel to the filter member 42, makes it possible for the observer to watch the accumulation of the foreign matter in the dirt collecting chamber. In fact, a salesman need not operate the machine, due to the provision of the dirt trap at the rear of the machine and the horizontal disposition of the window 47 and the filtering member 42, the prospective purchaser can propel the machine over the floor covering and at the same time observe through the window 47 the accumulation of foreign matter in the dirt collecting chamber. All of the dirt removed from the floor covering is collected and remains in full view within the dirt collecting chamber 50.

After the cleaning operation the dirt trap accessory is disconnected from the cleaner, and

the spring latch 35 released to open the cover 33. The mass of foreign matter 55 is then easily displaced, and the filtering member 42 is removed by grasping an exposed clean corner portion 56. The part of the filter exposed to the dirt laden air will be covered on one side with a deposit of foreign material, clear evidence, in addition to the mass 55 of foreign material of the amount of dirt which has been removed by operating the suction cleaner. A clean filter is used for each demonstration.

It is to be understood that the device functions without the usual dust filtering bag, and does not take the place of the latter, in the normal every-day use of the cleaner. The device is an accessory for the purpose of determining and observing the cleaning effectiveness of the cleaner, and the observing of the progressive accumulation of all the foreign matter as the floor covering is being cleaned. If desired the interior of the dirt collecting chamber 50 may be given a coat of white paint or provided with a suitable electric lamp to illuminate the dirt chamber.

I claim:

1. A demonstration dirt-trap for a suction cleaner comprising an air passageway, an air permeable dirt filter in said passageway to remove foreign material from air passing therethrough, and a window disposed substantially parallel to the filtering area of said filter to permit observation of foreign material collected thereon.

2. An accessory for demonstrating the cleaning effectiveness of a suction cleaner comprising, a casing member having a dirt chamber and provided with means adapted to detachably secure it to the exhaust of the suction cleaner in place of the usual cleaner filter bag, an air permeable dirt filter to remove foreign material from air passing through said casing, and a window mounted on said casing to permit observation of the foreign material removed from the surface undergoing cleaning and accumulating in said dirt chamber.

3. An accessory for demonstrating the cleaning effectiveness of a suction cleaner comprising, a casing member having a dirt chamber and provided with means adapted to detachably secure it to the exhaust of the suction cleaner in place of the usual filter bag, an air permeable dirt filter to remove foreign material from air passing through said casing, and a window mounted on said casing and disposed substantially parallel to and spaced from said filter to permit observation of the foreign material removed from the surface undergoing cleaning and accumulating in said dirt chamber.

4. An accessory for demonstrating the cleaning effectiveness of a suction cleaner comprising, a casing defining an air passageway having an inlet and a discharge normal with respect to each other, means for detachably connecting said casing to the exhaust of the suction cleaner to cause dirt-laden air to pass into said passageway, filter means carried by said casing in said discharge outlet, said filter means cooperating with said casing to define a dirt chamber and having a portion exposed to the outer atmosphere for escape of filtered air, a window so arranged in said casing with respect to said filter means whereby the operator of the suction cleaner observes the accumulation of foreign material on said filter means and in said dirt chamber as said suction cleaner is moved over the surface being cleaned.

5. An accessory for demonstrating the cleaning

effectiveness of a suction cleaner comprising, a casing having an air passageway and adapted to be detachably secured to the exhaust of the suction cleaner to cause dirt-laden air to pass into said passageway, filter means at the bottom of said casing cooperating with the latter to define a dirt chamber and having portions exposed to the outer atmosphere for escape of filtered air, a window arranged in the top wall of said casing 10 and parallel with respect to said filter means whereby the operator of the suction cleaner observes the accumulation of foreign material on said filter means and in said dirt chamber as said suction cleaner is moved over the surface being cleaned.

6. An accessory for demonstrating the cleaning effectiveness of a suction cleaner comprising, a casing having an air passageway and adapted to be detachably secured to the exhaust of the suction cleaner to cause dirt-laden air to pass into said passageway, filter means at the bottom of said casing cooperating with the latter to define a dirt chamber and exposed to the outer atmosphere for the escape of filtered air, a window 25 carried by said casing and in spaced parallel relation to said filter means, whereby the operator of the suction cleaner observes the accumulation of foreign material on said filter means and in said dirt chamber as the suction cleaner is moved over the surface being cleaned, and means movable with respect to said casing to permit re-

moval of the accumulated foreign material in said dirt chamber and for removably securing said filter means in said air passageway.

7. An accessory for determining the cleaning effectiveness of a suction cleaner comprising, a 5 casing having an air passageway and adapted to be connected to suction creating means, filter means in said passageway and disposed in a wall of said casing and cooperating with the latter to define a dirt collection chamber, said filter means 10 removing foreign material from said dirt-laden air and retaining the same in said dirt chamber, and a window carried by an opposite casing wall above and substantially parallel to said filter means for observing the accumulation of foreign 15 material on said filter means and in said dirt chamber as said suction cleaner is moved over the surface being cleaned.

8. A demonstration dirt-trap for a suction cleaner comprising, a casing defining an air passageway and having an inlet and an outlet normal to each other, said inlet of said casing being adapted to be connected to the suction creating means, a filter in said casing across said outlet to remove foreign material from air passing 20 through said casing, and a window carried by said casing to permit observation of the foreign material removed from the surface undergoing cleaning and accumulating in said dirt chamber. 25
